J. T. BAYARD

BARBER'S CHAIR

Filed Oct. 8, 1927

Inventor:
Joseph T. Bayard.
By Brayton Richards
Attest.

UNITED STATES PATENT OFFICE.

JOSEPH T. BAYARD, OF CHICAGO, ILLINOIS.

BARBER'S CHAIR.

Application filed October 8, 1927. Serial No. 224,912.

My invention relates to improvements in barbers' chairs and the like, and has for its object the provision of an improved construction of this character provided with means facilitating movements or adjustments thereof over a floor or the like.

Another object of the invention is the provision of a simple and effective construction of this character in which the working parts are concealed and protected.

Another object of the invention is the provision of a construction of this character which increases the effective base and thereby renders the construction more stable in use.

Other objects will appear hereinafter.

The invention consists in the combinations and arrangements of parts hereinafter described and claimed.

The invention will be best understood by reference to the accompanying drawings forming a part of this specification and in which—

Fig. 1 is a side view of a barber's chair embodying the invention; and

Fig. 2 a horizontal section taken substantially on line 2—2 of Fig. 1.

The preferred form of construction as illustrated in the drawings comprises an ordinary barber's chair having the usual back 5, seat 6 and foot rest 7, all mounted in the usual way upon a central stem 8 rotatably supported on a circular base 9 in the usual way. At its forward side so as to come directly under the foot rest 7, the base 9 is provided with a forwardly and transversely extending housing 10 in which is rotatably mounted a bearing roller 11 as shown, said roller being arranged to extend transversely and substantially tangentially with reference to the curved periphery of the circular base 9. The roller 11 is also set in the housing 10 to contact with the floor or other supporting surface 12.

In use the chair is set upon the floor with the roller 11 extending transversely, as shown, under the foot rest 7 when the chair is in position to receive a customer for bar-

bering attention. In such relation, it will be noted, that the effect of the construction is to extend the effective base under the foot rest 7 when it receives the weight of a customer seating himself in the chair and thereby tending to prevent tipping of the chair under such circumstances. When it is desired to move the chair all that is necessary is to tip the chair slightly forwardly, as indicated in dotted lines in Fig. 1, and whereby the weight of the chair will be thrown entirely upon the roller 11, and said chair thus readily moved or shifted into any desired position. The elongated form of the roller well adapts the same to carrying the comparatively heavy weight of the chair without injury either to the roller or to the floor surface over which the chair is moved. The bearing roller is entirely concealed and protected in the housing 10. It will also be noted that the appearance and proportion of the chair are improved by the attachment disclosed. The specific arrangement of parts is a simple and effective one for the purpose.

While I have illustrated and described the preferred form of construction for carrying the invention into effect this is capable of variation and modification without departing from the spirit of the invention. I, therefore, do not wish to be limited to the precise details disclosed but desire to avail myself of such variations and modifications as fall within the scope of the appended claim.

I claim:

A construction of the class described comprising a circular supporting base having a housing extending from one edge thereof; and an elongated roller arranged in said housing substantially tangentially to the edge of said base, said roller being arranged and adapted to bear the entire weight of said base when the same is tilted.

In witness that I claim the foregoing as my invention, I affix my signature this 4th day of October, A. D. 1927.

JOSEPH T. BAYARD.
